[57] CLAIM

The ornamental design for a collapsible hanging basket,
as shown and described.

DESCRIPTION

FIG. 1 is a front view of a collapsible hanging basket
embodying my new design, the rear view and two side
views being identical thereto.

FIG. 2 is a bottom view thereof, without the support
cords and hook.

FIG. 3 is a top view of FIG. 2; and

FIG. 4 is a collapsed side view of FIG. 2.
